UNITED STATES PATENT OFFICE

2,344,749

BUILDING WALL CONSTRUCTION

Frank W. Stevens, Syracuse, N. Y.

Application July 13, 1939, Serial No. 284,353

8 Claims. (Cl. 72—48)

This invention relates to a building construction and method that is adapted to provide a multiplicity of heat and dampness insulating cells within the building wall, while at the same time reinforcing the construction.

The invention is equally well adapted for outside walls, partitions, floors, and roofs, and where the term "wall" is used hereinafter it is intended, unless otherwise limited, to include all of these. The invention comprises a novel construction and method of using elements of sheet material to provide individual insulating cells within the walls that are separated from one another, and with wall ties of sheet material that reinforce the wall and hold the portions thereof at opposite sides of the insulating cells securely assembled, while at the same time serving to separate the insulating cells one from another. The sheet material employed in carrying out the invention may be sheet iron or steel, or other metal, or it may be water proofed card board, suitably reinforced if desired, or any other sheet material having a requisite factor of strength and stability. The sheet elements that are assembled to make up the insulating units are of simple and easily produced form and may conveniently be delivered to the building location as plain flat sheets to facilitate shipping and handling; such sheets to be shaped or cut or both, right on the construction job, with but little special equipment for this purpose. This method of procedure is also advantageous since it eliminates the necessity for carrying various sizes and shapes of the unit elements in stock. As to these insulating cell unit elements, it is to be noted that the smaller the individual hollow cells that are formed in the wall construction, the lighter may be the material from which the core or cell unit is made. The invention is well adapted, and as herein shown, for use in concrete building construction, but in its major aspects is also adapted for other types and materials for building.

It is to be noted that while the hollow insulating cells produced in building walls according to my invention, are of high heat insulating efficiency by reason of the dead air spaces provided, they may if desired be filled with insulating material either in solid form, such as asbestos, or they may be filled with a suitable chemical or gas or any other material to increase their insulating efficiency.

The foregoing and other objects and advantages of the invention will be better understood from the following detailed description, taken in connection with the accompanying drawings

wherein several illustrative embodiments of the invention are shown, and the distinctive features of novelty will be thereafter pointed out in the appended claims.

5 Referring to the drawings,

Figure 1 is a transverse section of a portion of a wall under construction in accordance with one form of my invention;

Figure 1a is a perspective view with an intermediate portion broken away showing one of the core units of this form;

Figure 2 is a view partly in section and partly in perspective showing a portion of the wall built up with the core units of Figure 1, and with the transverse wall ties assembled into the wall in a vertical position;

Figure 3 is a similar perspective and sectional view showing an arrangement wherein the wall ties are placed into the wall in a horizontal position;

Figure 4 is a perspective view showing a modified form of core unit elements wherein these elements are shaped and adapted to form double cells in the wall;

Figure 5 is a similar perspective view of the core unit elements showing them shaped and assembled to form triple cells in the wall;

Figure 6 is a transverse section showing a modified form of core or cell unit partially assembled into a wall;

Figure 6a is a perspective view of one of the cell elements as employed in Figure 6;

Figure 7 is a horizontal section of a wall portion showing still another form of core or cell unit built into a wall to provide insulating cells;

Figure 7a is a perspective view of one of the cell unit elements of the form of Figure 7;

Figure 7b is a similar perspective view showing a cooperative cell element for use with the same form;

Figure 8 is a sectional view of a wall portion showing in perspective a still further modified form of core units which are here adapted to dove-tail or interfit one into another;

Figure 8a is a perspective view of a core unit element as employed in the form of the invention shown in Figure 8;

Figure 9 is a transverse section of wall structure employing generally the form of cell units shown in Figure 1 but with a modification providing for a wall protrusion; a view on line 9a—9b. Figure 9a is a transverse section corresponding to Figure 9 but showing provision for a wall indentation instead of a protrusion;

Figure 10 is a horizontal section of a wall por-

tion showing provision for embedding necessary pipes and conduits in the concrete in connection with the use of the cell units of my invention;

Figure 11 is a horizontal section of a corner portion of a wall showing an adaptation of my invention thereto;

Figure 12 is a horizontal section of a wall portion at the locality of a partition showing an adaptation of my invention to provide strength and homogeneity with provision for the hollow cell units in both the main wall and the partition;

Figure 13 is a sectional view of a concrete floor portion showing in perspective a core unit assembly of my invention embedded therein, this view also showing an aligning key that may be used in the operation;

Figure 14 is a transverse section of a portion of a wall and floor, showing the connection of the floor to the wall;

Figure 14a is a fragmentary transverse section similar to Figure 14, but showing a still further modification of cell unit that may be employed in the floor;

Figure 15 is a vertical section at a corner of the top of the building showing a connection of the vertical wall to a relatively flat roof, both wall and roof equipped with the cell units of my invention which are arranged to provide a homogeneous construction at this level;

Figure 16 is a sectional view similar to Figure 15 but showing the application of the invention to a gable or like relatively steep roof;

Figure 17 is a fragmentary horizontal section showing a jamb construction for casement windows embodying the invention;

Figure 18 is a similar fragmentary section showing the application of the invention to a sill construction for casement windows;

Figure 19 is a fragmentary transverse section showing a jamb construction for sash windows; and

Figure 20 is a similar horizontal section showing the application of the invention to a jamb construction for doors, this being also an alternative method for casement windows when these are built up on the job.

Referring first to Figure 1, B indicates a wall "footing" or base upon the sides of which are erected the usual wall forms F. The hollow cell units of my invention are produced by providing sheet material elements 10 having an intermediate portion from the sides of which are bent in opposite directions at right angles, portions 10a, 10b. The lower extending portion 10b may have ears 11 struck inward therefrom adjacent its opposite sides while the upper extending portion 10a may have similar ears 12 struck outward therefrom. The lowermost one of these elements is embedded in the footing somewhat, as indicated at 13 and other like elements are erected thereupon, the ears 11, if used, resting upon the intermediate horizontal portion 10 of the next lower element, while the other side of the intermediate portion of the element rests upon the outwardly extending ears 12 of the next lower element. The ears 11 and 12 are not requisite but assist in positioning the units in uniform relation to one another. Thus these elements are adapted to build up a series of hollow cells intermediate the width of the wall, and these may be built up only as fast as the concrete is filled in, or they may be built up ahead of the concrete with the provision of spacers or wedge members S which fit between them and the wall forms as

indicated. In some instances it may be advantageous to tack-weld units together, or use one of the well-known liquid cements, or a dash of mortar to hold units in position until the concrete is poured. These cell elements 10 may be of any desired length, e. g. 12 inches or upwards (spacers if necessary to prevent buckling may be inserted inside large units), and between the abutting ends thereof are fitted metallic wall ties 14, these comprising plates which close the ends of the hollow cells and extend outward therefrom on each side into the concrete of the wall, these projecting extremities as shown in Figure 2, may be provided with a series of apertures or projections for more secure embedding in the concrete. These wall tie plates have the purposes, (1) of binding the double concrete wall and the hollow cells into a composite whole; (2) of comprising the ends of the hollow cells, thus becoming a part of the cells; and (3) of reinforcing the concrete.

The reinforcement thus produced by such metal wall tie is much more efficient than a similar amount of metal in any other form, because it contacts a greater amount of concrete and the contact is continuous.

In Figure 3 I show a form of the invention where the hollow cell elements 16 corresponding to the elements 10, and similarly produced, are set vertically instead of horizontally. In this case the wall ties or dividing plates are, of course, horizontally disposed. These plates 17 are shown in this form as having flanged sides 17a for more secure engagement with the concrete, it being understood that either such flanges, or the apertures 15, or both may be employed in either form of the invention. In this case as in that of Figure 1, a continuous series of individually isolated insulating cells is provided throughout the extent of the wall and intermediate the sides thereof.

In Figure 4 I show a form where the cell unit elements indicated at 18 are adapted to be built up into a double cell unit, such element being in this case produced with four rectangular bends successively in opposite directions as indicated at 18a, 18b, 18c, 18d. These may be provided with struck out ears similarly as the ears 11, 12 and built upon one another as seen to provide a double hollow cell wall.

In Figure 5 I show a form wherein the metal plates which form the cells are adapted to provide triple cells in the wall, each plate 19 for this purpose having six rectangular bends 19a, 19b, 19c, 19d, 19e, 19f; these elements being built up in the same manner as already described. This type of construction is particularly useful in cases where the wall is composed entirely or mostly of such cell unit assembly, i. e., without any substantial amount of concrete or other material at the sides thereof, or where such assembly is covered with but a thin material layer such as plaster, stucco, shingles, or the like. This multiple cell method of construction also provides more effective insulation, which makes it especially desirable for refrigerating purposes, warehouses, etc.

In Figures 6 and 6a I show a form wherein the cell unit elements are inverted U-shaped as indicated at 20. These are adapted to be nested one upon another to a small extent as indicated at 21 so that the frictional hold thus obtained is sufficient to keep them relatively in place as they are built up from the base B with the concrete deposit C applied at each side thereof as

in the forms already described, or ears such as 11 or 12 may be used. It will be understood that in this form as in each of the previous forms, transverse wall tie plates are interposed between abutting ends of these elements 20 to form individually isolated cells.

In the form of the invention shown in Figures 7, 7a, and 7b the cell unit elements are formed of U-shape as indicated at 22 with flange portions 22a extending from each extremity of the U-portion. These are assembled with the flange portions 22a of each element extending a small distance over the base of the U-portion of the next adjacent element as indicated at 23. This, of course, leaves the opening of the U-portions uncovered and plates 24 are provided for application to cover these spaces so that they provide alternate ones of the cells. In this form also it will be understood that transverse wall tie plates are assembled with the described members similarly as in the prior described forms to provide isolated insulation cells, and tie the wall portions together. In Figures 8 and 8a I show a form wherein the cell unit elements are formed of inverted U-shape as seen at 25, but with grooves or creases 26 formed at the sides of the base of such U-shape so that the edges of the side portions of the next element are adapted to interfit with, or dove-tail into such grooves as indicated at 27. The transverse wall tie plates are here indicated at 28.

In Figure 9 I show a form wherein cell elements 10 of Figure 1 are employed, but at the locality of a protrusion P in the wall a special cell element 29 is incorporated which is deeper so as to extend a farther distance into the protrusion P, this element being otherwise formed so as to interfit with the elements 10.

In Figure 9a, a special form of cell element 30 is illustrated for use at the locality of an indentation I in the wall, this unit differing from the elements 10 with which it is associated, only in being reduced in thickness as compared therewith.

In Figure 10 I show an adaptation of the invention to a wall construction wherein various pipes, flues, and conduits may be incorporated in the wall and in a novel association with the insulating cells of my invention. In this case the hollow cells may be produced of elements 10 similarly as in the first described form with transverse wall tie plates 14 as already described. As illustratively shown in this form a heating duct or flue 31 may take the place of one of the vertical cell unit series. Waste pipes, vents, or the like indicated at 32, 33 may be incorporated in the wall structure, the pipe 32 being shown as accommodated in an inner protrusion 34 of the wall, while the pipe 33 is fitted intermediate the width of the wall with one of the wall tie plates 14 at each side thereof. The wall tie plate 14 located adjacent the pipe 32 may have a bent extremity 140 to lie adjacent to, but clear the pipe 32. Other pipes as required, indicated at 35, and conduits 36 for various electric services may be embedded in the wall, a plug outlet for one of these being indicated at 37.

Figure 11 shows an illustrative application of my invention to the corner construction of walls. In this case the cell unit elements 10 leading up to the corner as already described, and the transverse wall tie plates 17 may be of a type already described. At the locality of the corner however, the wall tie plates 38, 39 at the ends of the adjacent cell units may be bent so as to extend

approximately in the diagonal direction of the corner as indicated at 38a, 29a and between them another wall tie plate 40, shown as somewhat longer, may extend in the diagonal direction of the corner.

In Figure 12 I show an adaptation of the invention for the junction of inner partitions with outer walls, the inner partition 41 being illustratively shown as not so thick as the main wall. 10 In such case the cell units indicated at 42 may be correspondingly of less width, and the transverse wall tie plates 43 likewise of less dimension. In such corner construction the wall tie plates at the locality of such junction indicated at 44, 15 45 may have an intermediate diagonal portion 46 extending across the corner with an extension 47 reaching into the concrete of the partition. The end of the cell units 42 at the locality of the wall junctions may have an especially formed wall tie 20 plate 48 with diagonally extending ends 48a extending across the corner and spaced from the tie plate portions 46.

Figure 13 shows an illustrative application of my invention to floor constructions. In this case a lower layer 49 of concrete is first placed over the floor forms, — then cell unit elements 50 and wall tie plates 51, similarly as already described, are inserted to some little depth into this concrete layer, while leaving a substantial open core area

If desired, the reinforcing tie-plates 51 may be of heavier material and extend from wall to wall to give strength to the floor. A second layer of concrete 52 is then applied to the top of the core units. In practice each core unit should be lapped over the next one about an inch as indicated at 53.

over the next one about an inch as indicated at 93 and these overlapping areas may be secured together by liquid cement, welding or otherwise. It will be noted that the wall tie plates bind the double layer of concrete and the core unit assembly into a composite whole, and these tie plates comprise the ends of the hollow cells likewise as in the vertical wall. It will also be noted that both layers of concrete are reinforced by the tie plates.

layers of concrete are reinforced by the core units at right angles to the tie plates. This produces an exceptionally strong floor, much in excess of ordinary needs. An aligning tool or key K may be provided so as to lock the core units and the wall ties at the proper level in the lower concrete layers. This invention is particularly applicable to

layer. This key has a hook or projection K' to engage the edges of the core unit elements, the core unit elements being pressed into the concrete until the end of the key reaches the floor form when the core unit or wall tie will be held an inch or thereabouts above the floor form by the projection K', whereupon by turning the key until the projection is disengaged from the cell unit, the key may be removed.

55 may be removed.

In Figure 14 I show a form of core unit elements 54 adapted for floor construction provided with a flat portion 55 so located with respect to the extent of the unit element that is adapted to rest on the top of the first layer of concrete 56 with the lower extremity of the core elements 57 spaced the desired distance above the bottom of the concrete. The floor "sleepers" 58 for a top floor 59 of wood, if desired, are embedded in the top layer of concrete to furnish a nailing piece for such wooden floors. The cell unit elements 60 adjacent the main vertical wall may have an extension 61 adapted to be embedded in the concrete of such vertical wall to further tie the floor to the wall.

In Figure 14a a modification of the core-unit elements adapted for floors is indicated at 62, this being adapted for use at an extremity of the floor and providing two flat surfaces 62a, 62b to rest

upon the lower layer of concrete, while also providing a flat surfaced upper extension 62c upon which the next adjacent core unit element may rest.

In Figure 15 I show an illustrative application of the invention to the junction of a relatively flat roof 63 to a vertical wall 64. This is similar to the provision for the floors already described, except that the hollow cells 65 produced by the core unit assembly 66 are formed thicker to provide more effective insulation. It is to be observed that the cell unit elements 67, 68 at the locality of the juncture of the roof and the vertical wall are extended and bent so as to extend from the roof into the concrete of the vertical wall, and from the vertical wall into the concrete of the roof respectively. In this Figure 14 indicates a portion of one of the wall tie plates.

Figure 16 illustrates the juncture of a steeper or gable roof 69 with an outer wall 70, and with a floor 71. This is accomplished similarly as already described, the cell unit elements at the locality of the angular bend from the wall to the roof having extended projections 72, 73 into the mass of the concrete to further reinforce the same, and the cell unit elements 74 at the juncture of the floor with the wall also having extensions 75 to be embedded quite some distance in the concrete of the wall.

Figure 17 illustrates a feature of construction adapted for the application of a casement window 76 with interposed caulking 77 against a ledge 78 of the concrete wall. In this case a bent wall tie unit may be provided with an intermediate portion 79 to close the adjacent cell units 80, and with angularly bent extensions 79a, 79b to extend into the concrete at the locality of the jamb.

Figure 18 shows another form of concrete reinforcement for the application of the casement window 76, this embracing angular extensions 81, 82 from the ends of the adjacent cell units and with an additional angular tie plate member 83 bent at an acute angle to reinforce the concrete to the best advantage.

Figure 19 illustrates a construction adapted for sash windows 84. In this case a reinforcing plate member 85 is provided with an intermediate portion adapted to rest against and close the adjacent cell unit 86, and having at one end portion a right angular extension 87 through the concrete, and having the other end portion reversely bent as indicated at 87' with an acute angle extremity 88 to best reinforce the concrete at the locality of the jamb.

Figure 20 illustrates a window construction with a jamb 89 which may also be used for door jambs if desired. In this case the end core unit assembly 90 has fitted thereto a reinforcing plate having an intermediate portion 91 to fit against the end of the cell unit with angular extremities 92, 93 to extend diagonally into the concrete mass.

It will thus be noted that in each of the described forms of the invention I provide hollow cell elements of simple form that are adapted to be shaped from flat sheet material on the construction job; that these elements are adapted to be quickly and easily interfitted with one another and assembled to constitute a continuous hollow cell formation in building walls or the like. Further that the described novel assemblage and cooperative arrangement of the transverse wall tie plates with the cell units affords a maximum of strength and reinforcement with a minimum use of material. A concrete wall produced as

described with an intermediate spacing of individually isolated hollow cells provide most effective insulation against heat and dampness, and this applies in equal degree to the application of the invention for roofs and floors as described.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having now described my invention, what I claim as new and desire to secure by Letters Patent is:

1. An insulating core assembly for building walls, comprising pieces of sheet material bent to angular form and interfitted one with another to constitute four sides of six-sided cells, and other pieces of sheet material fitted cross-wise in such assembly to close the remaining two sides of the cell units, said other pieces extending transversely outward from the cell unit assembly to constitute ties for embedding in cement, the entire assembly adapted to be embedded in plastic material.

2. A building wall having an interior insulating core with concrete or the like at each side of such core, said core composed of a multiplicity of angularly bent pieces of sheet material interfitted one with another to define four sides of six-sided cell units, and tie plates applied to such assembly to close the other two ends of the core units, said tie plates extending from the cell unit assembly at each side thereof, and embedded in the concrete, and adapted to tie the concrete sides and the intermediate core together and reinforce the same.

3. A cell-unit assembly for forming an insulating space in a building wall, comprising a series of rectangular elements of sheet metal each having two parallel, opposite, and substantially rectangular bends completely across the same and forming three planes, two of said planes adapted to form the front and top of one cell-unit, and the third plane forming the back of the cell-unit next above, said elements interfitted one with another, and transverse tie plates placed at each open end of each said interfitted cell-unit assembly to close said ends and make each such assembly form an individual dead-air space when the whole is embedded in concrete, the said tie plates projecting beyond the sides of the rest of the assembly so as to be embedded in the concrete and reinforce same.

4. An insulating core assembly for poured-concrete building walls, comprising elements of sheet material each bent to angular form to constitute in itself three sides of a rectangular cell each of said elements interfitted with a like element constituting a fourth side of said cell, and tie plates placed transversely at each open end of said cell to complete same, said tie plates extending transversely beyond said cell sides so as to be embedded in the concrete.

5. An insulating core assembly for poured-concrete building walls, comprising elements of sheet material each bent to angular form to constitute in itself two sides of a rectangular cell and interfitted with a like element to constitute four sides of said cell, and tie plates placed transversely at each open end of said cell to complete same, said tie plates extending transversely be-

yond the sides of said cells so as to be embedded in the concrete.

6. A building wall having an insulating core composed of a multiplicity of individual six-sided air cells with concrete or the like at each side of such core, each of said cells being formed by a rectangular element of sheet metal having two parallel, opposite, and substantially rectangular bends completely across the same and forming three planes, two of said planes adapted to form the front and top of one cell, and the third plane forming the back of the cell next above, said elements interfitted to form four sides of the cells, and tie plates applied to such assembly to close the other two sides or ends of the cell, said tie plates extending beyond the cell-unit assembly at each side thereof, the extended portions of said tie plates being embedded in the concrete to tie the concrete sides and the intermediate core together and reinforce the same.

7. A series of cell-unit elements for forming an insulating space in a building wall each comprising a strip of sheet material bent to substantially an inverted U shape with grooves formed along the top of the inverted U to receive and position the lower edges of another similar inverted U element and the last-named element placed thereon to form four sides of a rectangular cell.
10. 8. A six-sided cell-unit assembly for forming air cells in a poured-concrete building wall, comprising rectangular elements of sheet material bent to substantially U shape and each inverted and interfitted on top of another such element to form four sides of a cell, and tie plates placed transversely at each end of such cell to form the other two sides and complete the cell, said tie plates projecting transversely beyond the said elements for embedding in the concrete.
